UNITED STATES PATENT OFFICE.

ANGUS R. LE GRUE, OF BUFFALO, NEW YORK.

PUMPING APPARATUS.

Application filed November 9, 1925. Serial No. 67,733.

This invention relates generally to improvements in a pumping apparatus but more particularly to a novel mechanism for transmitting the reciprocatory motion to the 5 pump-pistons or plungers.

It has for one of its objects the provision of a mechanically-operated device of this character which is simple and inexpensive in construction, which is efficient and reliable in operation, and which is composed of 10 few parts so organized and arranged that they are not liable to get out of order.

Another object of the invention is the provision of a reciprocating motion transmitting mechanism for pumps and similar appliances which requires a minimum expenditure of power to operate it and which affords a material saving in cost of operation over the customary pumping mechanisms now in 20 use.

In the accompanying drawings:

Figure 1 is a top plan view of the pumping apparatus embodying my improvements. Figure 2 is a side elevation thereof. Figure 25 3 is an enlarged fragmentary longitudinal section on line 3—3, Fig. 1. Figure 4 is a transverse section on line 4—4, Fig. 3.

Similar characters of reference indicate corresponding parts throughout the several 30 views.

The operating parts of the pump-actuating mechanism are mounted on a suitable base or platform 10 and the pump cylinders 11, 12, two of which are shown, by way of 35 example, in connection with the mechanism are supported in a substantially horizontal position on a standard 13. Operating in these cylinders are pistons 14 having connecting rods 15 attached thereto and guided 40 for reciprocating movement in the cylinder heads 16.

Journalized in bearings 17 located near the ends of the platform 10 are horizontal, transverse shafts 18, 19, one or the other of 45 which is adapted to be driven by an electric motor or other source of power. 20, 20 indicate a pair of endless belts or sprocket chains disposed side by side and extending lengthwise of the platform 10 in substantially axial alignment with the pump-cylinders 11, 12. These chains pass around front and rear sprocket wheels 21, 22 which are mounted on the shafts 18 and 19, respectively, said chains being driven in unison 50 with the top stretches thereof traveling toward the pump-cylinders.

The movement of the sprocket chains is adapted to be transmitted to the pump-pistons 14 to reciprocate them alternately in opposite directions, each chain acting alternately to advance one piston and simultaneously return the companion one. To this end, the outer or rear ends of the piston rods 15 are fastened to cross-heads 23 guided for horizontal movement on longitudinal 65 rails 24 supported at their ends on transverse brackets 25 rising from the platform 10. Depending from the underside of each guide-head is a tappet or finger 26, U-shaped in cross-section, which is arranged to straddle 70 the upper stretch of the corresponding driving chain 20, as shown in Fig. 4. Each chain is provided with a pair of transverse coupling pins 27 which extend from opposite sides of said chain and which are adapted, 75 at predetermined intervals to encounter the tappet on the corresponding cross-head 23 and thereby transmit the movement of the chain to the piston. The distance between the coupling pins of a pair on each chain 80 is approximately equal to the combined forward and return strokes of one of the pistons, so that these pins act alternately on the corresponding cross-head tappet 26 to advance the piston in its cylinder. The relative positions of the coupling pins on both chains is such that while one of the pins of a pair on one chain is engaged with the corresponding tappet for causing the companion piston to be moved forwardly in its 85 cylinder, the pins on the other chain are traveling idly until a predetermined point is reached where one or the other of them encounters its corresponding cross-head tappet to move the other piston forwardly in 90 its cylinder. In other words, these parts are so organized and arranged that the chains 95 act alternately and independently to force the respective pistons forwardly in their cylinders. At the end of the forward or down-stroke of the piston, that particular coupling pin 27 in engagement with the corresponding cross-head tappet 26 gradually recedes and is ultimately disengaged from the latter by reason of the driving chain passing downwardly around its front sprocket wheel 21. At this time, one of the coupling pins of the 100 companion driving chain encounters the tappet of the other cross-head and thereupon the corresponding piston is moved forwardly 110 in its cylinder.

As one of the pistons is moved forwardly

in its cylinder, the companion piston is simultaneously moved rearwardly in its cylinder through the medium of a connection between the cross-heads of the respective pistons. The preferred mechanism for accomplishing this result consists of a flexible member or chain 28 connected at its ends to links 29 attached to the respective cross-heads 23 and passing intermediate its ends around a sprocket wheel 30 free to turn on a vertical arbor or spindle 31 carried by a plate or supporting member 32 fastened to the rear guide-rail bracket 25, as shown in Figs. 2 and 3. It will thus be seen that as one of the pistons is moved forwardly in its cylinder, the adjacent stretch of the chain 28 is moved in the same direction with it, while the opposite stretch, which is connected to the cross-head of the other piston, is drawn rearwardly or in the reverse direction and moves such piston with it to effect the return stroke thereof.

By this improved pumping apparatus, a constantly driven set of endless belts or chains is utilized to smoothly and positively transmit reciprocating motion to the pistons of a pump which may be used for pumping air, water or gas and other purposes. Furthermore, only a minimum expenditure of power is required for operating the mechanism and a material saving of labor, oil and

fuel is afforded over the pump equipment now in use.

I claim as my invention:—

In an apparatus of the character described, 35 the combination with a pair of cylinders and pistons including connecting rods operable therein, of a supporting base, front and rear shafts journaled on said base and each having a pair of sprocket wheels thereon, means 40 for driving one of said shafts, sprocket chains passing around said wheels and provided at intervals with coupling pins, guide rails arranged parallel with said chains and disposed above the upper operative stretches 45 thereof, cross-heads applied to the piston-rods and guided on said rails, tappets depending from the cross-heads and disposed in the path of movement of said coupling pins to be alternately engaged with and disengaged from the tappets at predetermined 50 points in the travel of said chains whereby the pistons are advanced in their cylinders, a sprocket wheel located above and between the operative stretches of the driving chains, 55 and a chain fastened at its ends to said cross-heads and passing intermediate its ends around said last-named sprocket-wheel, whereby the return of one piston is effected simultaneously with the advance of the companion piston.

ANGUS R. LE GRUE.
